COMBINATION LIGHTER AND BURNER
SUPPORT FOR GAS STOVESStanley H. Hobson, Rockford, Ill., assignor to
Geo. D. Roper Corporation, Rockford, Ill., a
corporation of Illinois

Application November 7, 1931, Serial No. 573,595

17 Claims. (Cl. 126—39)

This invention relates to a combination lighter and burner support for the cooking top of a gas range, and is an improvement on that covered in my copending application, Serial No. 5 468,283, filed July 16, 1930.

The principal object of the present invention is to provide a structure generally similar to that disclosed in the other application but made up of parts which, when assembled without certain 10 top parts, form a structure adapted for push button lighting, and which when assembled with the top parts included, form a structure adapted for automatic lighting on the flash-back principle. In accordance with this object, I provide an opening 15 in the main bracket for removably receiving a pilot light housing of the type suitable for flash-back lighting, the same being constructed so as to be mated with the top parts which form tunnels on the secondary burner supporting brackets, 20 so as to hold the housing in place and insure the proper relationship with the tunnels for ignition of gas conducted through the tunnels from the burners for flash-back lighting. This construction permits dispensing with the housing and 25 the top parts if push button lighting is to be used, in which case the housing of the push button lighter is arranged to be entered through the opening in the main bracket so as to be properly disposed with respect to the burners carried 30 on the secondary brackets.

Another object is to provide a structure of the kind mentioned adapted for use interchangeably with ranges having right or left hand ovens.

Still another object consists in improvements 35 in the supports for the burners with a view to more accurately locating the burners with respect to the lighter, as desired in the case of flash-back lighting particularly.

40 The invention is illustrated in the accompanying drawings, in which—

Figure 1 is a plan view of the cooking top of the gas range embodying my invention, the grates being removed to better disclose the invention;

45 Figs. 2, 3 and 4 are sections on the correspondingly numbered lines of Figure 1;

Fig. 5 is a cross-section on the line 5—5 of Fig. 4;

Fig. 6 is a horizontal section through the structure appearing at the center of Figure 1;

Fig. 7 is a plan view of the combination lighter and burner support shown in Figure 1 but with the top parts left off, as for push-button lighting;

Fig. 8 is a similar view but showing a modified or alternative construction;

Fig. 9 is an underside view of one of the burners;

Fig. 2a is a view similar to Fig. 2 but showing the top parts removed for push button lighting, and a push button lighter substituted for the flash-back lighter, and

Fig. 4a is a view similar to Fig. 4 but showing a modified or alternative construction of the 10 burner support.

Similar reference numerals are applied to corresponding parts throughout the views.

Referring to Figure 1, the numeral 10 is applied to the frame of the cooking top alongside the 15 oven section (not shown), which in this case is to the right of the cooking top but may, however, be to the left thereof, as is well known. The usual grates provided for the cooking top and fitting in the recess 11 have been removed, better to disclose the cooking top burners 12—15, and the simmer burner 16. The burners 13—15 are preferably of identical construction, and the burner 12 of the same construction but of slightly larger size, all having a neck 17 of the same 20 length, into which the tapered end of the mixing tube is arranged to be entered and suitably secured, as by means of a set screw. This means a saving in cost because the same burners can be used for front or back, right or left, by simply 25 providing the proper length and shape of mixing tube and attaching the same thereto, as stated. The mixing tubes all make detachable connection with cocks 18 on the manifold 19. In accordance with the other application, I have provided a combination lighter and burner support, indicated generally by the reference numeral 20, 30 centrally disposed with respect to the burners 12—15 for the purpose of affording a central support for said burners, as well as a central lighter, 40 for uniformly good support and uniformly good lighting. The structure 20 of the present invention, as hereinafter described, is so constructed that it can be used in one way, with certain parts omitted, for push button lighting, and can be 45 used another way, with the other parts included, for flash-back lighting.

The combination lighter and burner support 20 comprises a main supporting bracket 21, secondary burner supporting brackets 22 and 23, a 50 flash-back lighter housing 24, and top funnel-forming parts 25 and 26. The main bracket 21 has a lug 27 arranged to rest on a ledge 28 on the frame 10 to provide one point of support at one end of the bracket, and has a cross portion 55

29 on the other end thereof having two lugs 30 thereon for reception on similar ledges provided therefor on the frame 10 to provide two other points of support for the bracket. This three-point support assures the rigidity of the bracket and the disposition thereof in the proper plane with respect to the cooking top. Lugs 31, provided on the frame 10 of the cooking top, have engagement with the cross portion 29 of the bracket from above so as to keep the same seated solidly on its ledges in the frame. The interlocking of the parts permits quick and easy assembling. The main bracket 21 has an opening 32 provided in the middle thereof, at which point the bracket is of increased width to provide a broad flat seat 33 on which to set the secondary brackets 22 and 23 (see Fig. 7). Small depressions 34 are formed in the four corners of the seat 33 to receive downwardly projecting bosses 35 provided on the secondary brackets, and upwardly projecting U-shaped ribs 36 are formed at opposite ends of the seat for reception of lugs 37 on the secondary brackets, whereby to accurately locate said brackets with respect to the bracket 21 and in a predetermined relation to the opening 32. When the brackets are thus located, holes therein register with holes in the bracket 21 so that bolts 38 can be entered through the parts to fasten the same together in the manner shown in Figs. 2a and 7.

The secondary brackets 22 and 23 reach out beneath the cooking top burners, as shown in Figure 1, and have the outer ends thereof constructed to serve as supports for the burners. The same each has an upwardly projecting forked lug 39 near the outer end, and a plain upwardly projecting lug 40 at the outer end. The bottom of each burner is, on the other hand, provided with a flat annular face 41 around the center thereof to rest on the lug 40, and has downwardly projecting radial ribs 42 on four of the eight fingers of the burner at the outer ends thereof, slotted transversely as at 43 for interlocking engagement with the forked lug 39. Each burner is, therefore, supported centrally by a lug 40 and marginally by a lug 39 which at the same time, by reason of the interlocking of said lug with the rib 42, holds the burner in a predetermined position (see Figure 1). The cooking top burners 12-15 are all supported in the same way from the main bracket 21 and are, therefore, assured of proper relationship to whatever form of lighter is used in the opening 32. The secondary brackets, instead of being cast as separate pieces, may be cast as integral extensions, as shown in Fig. 8, at 22' and 23'. The only objection to a bracket 21' of this construction is the difficulty in the molding operation, and for that reason the plural part construction is preferred.

60 A push button lighter housing is shown at 24' in Fig. 2a entered through the opening 32, its tip 44 being connected by means of a tube 45 with the valve 46 communicating with the manifold 19. 47 is the regulating screw whose adjustment determines the size of the pilot light, and 48 is the push button, the depression of which causes jets to be flashed from the housing 24' in four directions for lighting whatever burner or burners are turned on at the time. So much for the push button lighting phase of my invention.

The opening 32 is preferably flared upwardly, as indicated in Fig. 2, and the flash-back lighter housing 24 has the lower portion thereof conformed spherically or on a taper to fit in and center itself in said opening. Three equally

spaced lugs 49 are provided in the bottom of the housing projecting radially inwardly to locate the tip 50, forming the pilot light, centrally with respect to the housing and with respect to the baffles 51 provided therein in accordance with the disclosure in the copending application of Peter I. Holman, Serial No. 564,502, filed September 23, 1931. The tip 50 is connected by a tube 52 with the manifold 19, and a valve 53 provides a means of regulating the flow of gas to the tip to secure the proper sized flame. Now, the housing 24, as best appears in Fig. 6, has a pair of necks 54 openings from opposite sides of the pilot light chamber 55 therein, and into either one of these a flash-back tube 56, extending from the oven section, is arranged to be entered, the right hand neck being used in the present case because of the right hand oven. Gas conducted through the tube 56 when the oven burner is turned on is ignited in the pilot light chamber 20 and a flash-back occurs through the tube to automatically ignite the burner. The simmer burner 16 is placed in proximity to the outer end of the other neck 54, as shown in Figure 1, and is so close to the pilot light chamber 55 that it is easily ignited through the neck 54 when turned on. Ledges 57 are formed on the secondary bracket 23 to either side of the bracket 21 to support the simmer burner in either of its positions. It is, therefore, apparent that the construction 30 is adapted for use interchangeably with stoves having right or left hand ovens, the flash-back tube 56 being in either case entered in one of the necks 54, and the simmer burner 16 being placed alongside the other neck.

The top parts 25 and 26 are adapted to cooperate with the secondary brackets 22 and 23, respectively, or 22' and 23', respectively, as the case may be, to form tunnels 58 for conducting gas from end ports 59 on the adjacent fingers of the various cooking top burns 12-15 to the pilot light chamber 55 for ignition, whereby to light said burners by the flash-back through said tunnels. The top parts 25 and 26 are cast to provide arms channel-shaped in cross-section, as best appears in Fig. 5, so as to provide the tunnels 58 when the parts are superimposed on the brackets, the arms being further conformed to the shape of the brackets, as clearly indicated in Figs. 2-4, so as to form tunnels that are reasonably gas-tight. Longitudinal rib 60 projecting downwardly from the sides of the channel of each arm on the parts 25 and 26 serve to locate the same properly on the brackets 22 and 23 so that the parts can be held in place well enough, each by the one bolt 38 entered through a hole in the web 61 provided between the arms of each of said parts. The arms of each of the top parts 25 and 26 terminate in slightly spaced relation to the outer ends of the fingers of the burners with which the same are to cooperate, so that the end ports 59 are properly aerated and there is, furthermore, the proper space through which to ignite the burners by flash-back through the tunnels. The brackets 22 and 23 are formed, as best appears in Fig. 4, to locate outer ends of the tunnels 58 at the proper elevation with respect to the tops of the burners, it being found that the best results are secured if the top of the burner is in a plane running through the center of the outer end of the tunnel. With that relationship, the gas issuing from the end ports 59 is also assured of proper entry into the tunnels. The parts 25 and 26 have ribs 62 projecting therefrom for entry in openings 63 provided therefor in the opposite

sides of the housing 24 so as to make gas-tight connections with the housing 24 and establish good communication between the tunnels 58 and the pilot light chamber 55. The entrance of the ribs 62 into the openings 63 serves also to hold the housing 24 in place. That is to say, the bolts 38 hold the entire assembly together on the bracket 21. It is no doubt evident that when any one or more of the burners are turned on, gas issuing from the end port 59 in each case is conducted through the tunnel 58 associated therewith and is ignited in the pilot light chamber 55, and a flash-back occurs through the tunnel and lights the burner or burners.

In conclusion, attention is called to Fig. 4a showing a modified or alternative construction for the burner supports. Instead of providing the lugs 39 and 40 and the cooperating face 41 and rib 42, above described, a lug 64 can be cast integral with the one finger of the burner and made T-shaped in horizontal cross-section to provide opposed flanges 65 to fit in a T-slot provided therefor in the outer end of the bracket 22a cooperating with the aforesaid burner. The T-shaped lug fitting in the T-slot naturally permits of quick and easy assembling or disassembling, and at the same time better insures rigidity of the burner than is secured with other supports. An outwardly projecting lug 67 on the bracket below the T-slot serves as an abutment for the T-shaped lug and determines the elevation of the burner with respect to the bracket, and, hence, with respect to the tunnel 58 adapted to cooperate therewith. With this construction, it is manifest that the top of the burner can be accurately located in a plane running through the middle of the outer end of the tunnel that is to cooperate with the end port 59 of said burner, and the burner is bound to remain in a truly horizontal plane parallel with the plane of the cooking top so as to give best performance.

It is believed the foregoing description conveys a good understanding of all of the objects and advantages of my invention. The appended claims have been drawn with a view to covering all legitimate modifications and adaptations.

I claim:

1. In a gas stove, the combination with the burners of the cooking top, of a spider support centrally disposed with respect to the burners having supporting arms extending toward the different burners, means thereon for supporting the burners, a pilot light housing centrally disposed on said support, and top parts fitting over the supporting arms to form tunnels for conducting gas from the different burners to the pilot light housing for ignition and for conducting the flashback after ignition to the burners.

2. In a gas stove, the combination with the burners of the cooking top, of a spider support centrally disposed with respect to the burners having supporting arms extending toward the different burners, means thereon for supporting the burners, a pilot light housing centrally disposed on said support, said housing being a separate unit removable from the support, and top pieces removably secured in place holding the pilot light housing in assembled position, said top pieces being so related to the aforesaid supporting arms to form gas-conducting passages between the pilot light housing and the different burners.

3. In a gas stove comprising a cooking top and burners therefor, a main supporting bracket reaching fore and aft with reference to the cook-

ing top between the right and left hand burners, secondary brackets supported on the main bracket and reaching laterally therefrom for supporting the right and left hand burners in a certain plane with respect to the cooking top, the main bracket having an opening provided therein centrally with respect to the burners, a pilot light housing disposed in said opening, and top members superimposed on the secondary brackets and forming gas-conducting passages between the pilot light housing and the different burners.

4. A structure as set forth in claim 3 including means for jointly securing the top members and the secondary brackets to the main bracket.

5. A structure as set forth in claim 3 wherein the pilot light housing is removably mounted in the opening in the main bracket, and wherein the top members are arranged when secured in place to hold the housing in assembled position.

6. A structure as set forth in claim 3 wherein the pilot light housing is removably mounted in the opening in the main bracket, and wherein the top members are arranged when secured in place to hold the housing in assembled position, the structure including means for jointly securing the top members and the secondary brackets to the main bracket.

7. In a gas stove, the combination with the burners of the cooking top, of a spider support centrally disposed with respect to the burners having supporting arms extending toward the different burners, means thereon for supporting the burners, said support having a central opening provided therein from which the supporting arms radiate in planes at a predetermined elevation relative to the top of the opening, a pilot light housing constructed for reception in said central opening and having openings provided in the side walls thereof in line with the inner ends of said supporting arms, and top members fitting removably over the supporting arms to form tunnels for conducting gas from the different burners to the pilot light housing for ignition and for conducting the flashback after ignition to the burners.

8. In a gas stove, the combination with the burners of the cooking top, of a single bracket structure for supporting all of said burners in a certain plane with respect to the cooking top, the same comprising supporting arms reaching in different directions from a central opening provided in said bracket structure, and automatic lighting means comprising a pilot light housing disposed in said opening, and gas conduits reaching therefrom in different directions and shaped to correspond to said supporting arms and resting on top of the latter.

9. In a gas stove, the combination with the burners of the cooking top, of a single bracket structure for supporting all of said burners in a certain plane with respect to the cooking top, the same comprising supporting arms reaching in different directions from a central opening provided in said bracket structure, and automatic lighting means comprising a pilot light housing disposed in said opening, and inverted channel-shaped conduits extending in different directions from said pilot light housing, said conduits being shaped to correspond to said arms and having downwardly projecting flanges on the sides thereof to fit alongside the longitudinal edges of said arms whereby to locate the conduits in proper relation to the arms to form tunnels between the arms and conduits for conducting gas from the different burners to the pilot light housing for

ignition and for conducting the flash back after ignition to the burners.

10. In a gas stove, the combination with the burners of the cooking top, of a combination lighter and burner support of sectional construction, the same comprising a sub-structure formed to provide arms to support the burners in a certain plane with reference to the cooking top, and a super-structure detachably mounted on the sub-structure and including a pilot light housing and portions which with the aforesaid arm form gas conduits extending from said housing toward the different burners.

15. In a gas stove, the combination with the burners of the cooking top, of a sectional bracket structure, consisting of a sub-structure constructed so as to support the burners in a certain plane relative to the cooking top, a super-structure thereon of similar form and complementary to the sub-structure and constructed so as to provide passages between said structures open at one end to the different burners, and lighting means operative at the other end of said passages.

20. 12. In a gas stove, the combination with the burners of the cooking top, of a sectional bracket structure, consisting of a sub-structure constructed so as to support the burners in a certain plane relative to the cooking top, the sub-structure having a central support for a lighter, a lighter on said support, and a super-structure of similar form to the sub-structure for assembly removably upon the sub-structure to provide passages between said structures communicating at one end with the lighter on said support and at the other end with the various burners.

25. 13. In a gas stove comprising a cooking top and burners therefor, a lighter composed of a plurality of sections constructed to be placed on top of one another and interfitted so as to provide a pilot light housing, and gas conduits communicating therewith and extending to the burners to conduct gas from the burners to the housing for ignition therein, whereby to ignite the burners by flash-back, certain of said sections being further constructed so as to support the burners adjacent the outer ends of said conduits, and means for securing the interfitting sections together into a unitary assembly.

30. 14. In a gas stove comprising a cooking top, burners in the four corners of the cooking top, a spider frame rigidly supported in a central position at a certain elevation relative to the cooking top and providing arms extending therefrom toward the various burners, the outer ends of said arms being constructed to support the burners, whereby said frame constitutes a unitary burner support, said frame having an opening provided therein substantially equi-distant from

the various burners, a lighter comprising a housing demountably received in said opening, and top pieces fitting over the arms of the spider frame and engaging said housing to hold the same in position, the top pieces being removably mounted on said spider frame and being constructed to provide gas conducting channels extending from the burners to the housing.

35. 15. In a gas stove comprising a cooking top, burners in the four corners of the cooking top, a lighter frame extending in the middle of the cooking top between the two pairs of burners and rigidly supported at a certain elevation relative to the cooking top independently of the burners, said frame having an opening provided therein centrally with respect to the burners, a pilot light housing entered in said opening, brackets for supporting said burners demountably supported on said frame, and means on the frame for locating and fastening said brackets on the frame in a predetermined relation to the central opening, whereby to support said burners in operative relationship to the pilot light housing.

40. 16. In a gas stove comprising a cooking top, burners in the four corners of the cooking top, a lighter frame extending in the middle of the cooking top between the two pairs of burners and rigidly supported at a certain elevation relative to the cooking top independently of the burners, said frame having an opening provided therein centrally with respect to the burners, a pilot light housing entered in said opening, brackets for supporting said burners demountably supported on said frame, top members demountably supported on said frame with the brackets to provide gas conducting channels between the burners and the pilot light housing, and means on the frame for locating and fastening said brackets and top member on the frame in a predetermined relation to the central opening, whereby to support said burners in operative relationship to the pilot light housing.

45. 17. In a gas stove, the combination with a cooking top, of a burner support comprising a spider having burner supporting arms, cooking top burners at the outer ends of said arms, means integral with the outer ends of said arms supporting said burners, whereby the spider and burners form a unit arranged to be supported at a predetermined elevation relative to the cooking top with all of the burners disposed in the same operative relation to the cooking top, said spider being constructed to receive a lighter centrally located with respect to the burners and burner supporting arms, and means detachably mounted on the arms of said spider providing gas conducting passages between the burners and the lighter.

STANLEY H. HOBSON.
